US00D484707S

(12) **United States Design Patent** (10) Patent No.: **US D484,707 S**
Kraker (45) Date of Patent: ** Jan. 6, 2004

(54) **PATTERN FOR A SYNTHETIC THERMOSET SOLID SURFACE MATERIAL**

(76) Inventor: **Patrick O. Kraker**, 1800 Westminster Pl., Oklahoma City, OK (US) 73120

(**) Term: **14 Years**

(21) Appl. No.: **29/169,743**

(22) Filed: **Oct. 25, 2002**

(51) LOC (7) Cl. **05-06**

(52) U.S. Cl. **D5/43**

(58) **Field of Search** .... D5/1, 2, 3, 7, D5/8, 11, 19, 20, 23, 25, 30, 32, 41, 44, 43, 45, 46, 47, 49, 50, 52, 53, 54, 55, 56, 57, 58, 59, 60, 61, 62, 63, 64, 99; D2/749, 994; D6/582, 583, 595, 596, 598, 603, 604, 605, 608, 613, 616, 617, 622; D24/124, 125; D25/142, 152; 428/17, 18, 151, 154, 156, 171, 187, 198, 199, 540, 542.2, 542.6, 904.4, 919, 413 AM, 709; D7/396.4, 396.5; 162/134, 231, 140; 156/209, 148

(57) **CLAIM**

The ornamental design for a pattern for a synthetic thermoset solid surface material, as shown and described.

DESCRIPTION

The sole FIGURE is a top plan view of a pattern for a synthetic thermoset solid surface material, showing our new design.

1 Claim, 1 Drawing Sheet
